UNITED STATES PATENT OFFICE.

JOHN S. CONNELLY, OF PORT ARTHUR, TEXAS.

AUTOMATIC FUEL-CHANGING VALVE.

1,260,756.

Specification of Letters Patent. Patented Mar. 26, 1918.

Application filed March 16, 1917. Serial No. 155,374.

To all whom it may concern:

Be it known that I, JOHN S. CONNELLY, a citizen of the United States, residing at Port Arthur, in the county of Jefferson and 5 State of Texas, have invented certain new and useful Improvements in Automatic Fuel-Changing Valves, of which the following is a specification.

In many sections of the country, natural 10 gas is supplied for fuel purposes at comparatively low cost and is, for many purposes, an ideal fuel. It not infrequently happens, however, that for longer or shorter periods of time the supply of natural gas 15 is entirely cut off, or so reduced, that plants depending thereon have to be shut down, unless arrangements be made for operating them with other fuel.

It is the object of my invention to provide 20 an automatic mechanism, especially adapted for use in connection with small plants employing an internal combustion engine as the motor, that will operate to supply such engine with gas so long as the 25 pressure in the gas system is above a certain amount, and to automatically cut off the connection with the gas supply and at the same instant put the engine in communication with a supply of liquid fuel, whenever 30 the supply of gaseous fuel is reduced beyond a determined amount, as indicated by the pressure in the gas supply system.

In the accompanying drawings, Figure 1 35 is an elevation of apparatus embodying my invention.

Fig. 2 is a section through the controlling valve and some of the adjacent parts.

In the accompanying drawings, 2 represents 40 a fuel supply pipe leading to an internal combustion engine, not shown, the fuel being in gaseous or vapor form. 3 indicates a service pipe connected with a system that supplies natural or artificial gas, and 4, a liquid fuel pipe, communicating 45 with a source of supply that will be individual to the plant with which my apparatus is used. The three pipes thus far referred to connect respectively with a three-way valve 5. The ports and passages 50 in the turning plug of the valve are so disposed, that when one source of supply is in communication with pipe 2 leading to the engine, the other supply source is cut off, and vice versa, as indicated in Fig. 2. An 55 adjustable valve 7 connected with the supply pipe 2 is employed to regulate the

amount of air admitted to such pipe to be mixed with the fuel to produce the readily inflammable charges that are successively delivered to the internal combustion engine. 60 It will be understood that the pipe 4 is open and in free communication with the oil supply, so that whenever the three-way valve 5 is turned to put the engine in communication with the said pipe 4, then oil will be 65 drawn by suction through the pipe 2 and into the engine cylinder.

The rotary plug of the valve 5 is provided with an exterior arm 10, by which the valve may be manipulated. 70

11 indicates a diaphragm controller of suitable construction, connected by a pipe 12 with the gas supply system, so that the operation of the diaphragm is controlled by the pressure of gas in such system. Connected with the movable diaphragm of the controller, so as to be moved thereby, is a stem 13, that engages with and operates a lever 14, which in turn is connected by a cord 15 with the arm 10 of the three-way 80 valve. Upon the lever 14 are suitable counter-balancing weights 16, and connected with the arm 10 are other counter-balancing weights 17, these being used or not as circumstances may require, in order 85 that the parts shall move with sufficient freedom and ease.

It is to be understood that when an apparatus such as I have described and illustrated is used, the engine will be run by gas 90 whenever that is practicable, and that resort to the supplemental liquid fuel supply will be had only when the supply in the gas system, and incidentally the pressure therein, is so reduced, from one cause or another, 95 that sufficient fuel will not be supplied to properly operate the engine. Under normal conditions, the parts occupy the positions indicated by dotted lines in Fig. 1 of the drawings, that is, the diaphragm is distended, and the valve, through its connections with the diaphragm, is turned into the position indicated in Fig. 2, putting the gas supply pipe 3 into communication with the engine-connected pipe 2, and at the same 100 time cutting off communication between the engine pipe and the liquid fuel supply. When, however, the pressure in the gas system falls to such a degree that the diaphragm is no longer distended, thereby indicating 105 that pipe 3 will not supply sufficient fuel to run the engine, the parts automatically 110

assume the positions indicated in full lines in Fig. 1, cutting off communication between the engine and the gas supply, and establishing a communication with the fluid fuel supply. This change of connections, between engine and source of supply, is not only automatic, but practically instantaneous, so that the running of the engine is not stopped by such change, nor is its speed materially affected.

As stated, my invention is intended particularly for use in connection with small power plants, such, for instance, as are used to generate electricity for a single dwelling or establishment, and it has therefore been devised so as to be entirely automatic in its operations, thus making the services of an attendant unnecessary; to be simple in construction, so that it is not liable to get out of order; reliable in operation, and cheap in cost, so that it may be economically used in small unit plants.

I have deemed it unnecessary to illustrate the engine or motor and the means for starting and stopping the latter, as these may be of many different kinds and types well known in the art. I have also thought it unnecessary to show more than one means or connection by which the diaphragm operates the three-way valve; for, while this is a form of connection that I have used with success, others for accomplishing the same results and coming within the principle of my invention, will readily suggest themselves to those skilled in the art.

What I claim is:

1. In apparatus for automatically changing from one kind of fuel to another in operating internal combustion engines, the combination of a fuel supply pipe leading to the engine, a service pipe connected with a gas supply system leading to the said engine supply pipe, a service pipe connected with a supply of liquid fuel leading to the engine supply pipe, valve mechanism arranged to completely cut off one source of supply to the engine pipe and simultaneously establish the other and vice versa, and automatically operating means controlled by the pressure of gas in the gas supply system for operating the said valve mechanism to cut off the gas supply when the pressure falls below a determined degree and to restore it when the pressure is above that degree.

2. In apparatus for automatically changing from one kind of fuel to another in operating internal combustion engines, the

combination of a fuel supply pipe leading to the engine having independent connections for delivering thereto respectively gaseous fuel and liquid fuel, a single valve for controlling the supply from said connections and automatic means controlled by the pressure of the gaseous fuel being delivered arranged to operate the said valve substantially as and for the purposes set forth.

3. In apparatus for automatically changing from one kind of fuel to another in operating internal combustion engines, the combination of an engine supply pipe, a gaseous fuel supply pipe, a liquid fuel supply pipe, a single three-way valve device connecting the said three pipes and means for operating the valve controlled by the pressure of the gaseous fuel being supplied, arranged to cut off such gas supply when the pressure falls below a determined degree and simultaneously turn on the supply of liquid fuel, and to cut off the latter and restore the supply of gaseous fuel, when the pressure of the latter again increases.

4. In apparatus for automatically changing from one kind of fuel to another in operating internal combustion engines, the combination of an engine supply pipe, a gaseous fuel supply pipe, a liquid fuel supply pipe, a single three-way valve connecting the said three pipes, an adjustable air valve connected with the supply pipe, and automatic means controlled by the supply of gaseous fuel for operating the said three-way valve.

5. In apparatus for automatically changing from one kind of fuel to another in operating internal combustion engines the combination of an engine supply pipe, a service pipe connected with a gas system, a supply pipe leading from a source of liquid fuel individual to the apparatus, a single three-way valve device connecting the said three pipes and controlling the flow from the fuel supply pipes to the engine supply pipe, a diaphragm controller connected with the gas system and arranged to be operated by the pressure of the gas therein, and motion-transmitting connections between the diaphragm of the controller and the three-way valve arranged to move the latter to put the gas service pipe in communication with the engine when the pressure of gas is above a determined degree, and at the same time cut off the connection with the liquid fuel supply, and to cut off the gas supply and turn on the liquid fuel supply when the pressure falls below the said degree.

JOHN S. CONNELLY.
